UNITED STATES PATENT OFFICE.

WALTER S. ROCKEY AND HILLIARY ELDREDGE, OF NEW YORK, N. Y., ASSIGNEES TO
METALLURGICAL RESEARCH COMPANY, A CORPORATION OF ARIZONA.

FURNACE.

1,057,883.

Specification of Letters Patent.

Patented Apr. 1, 1913.

Application filed June 3, 1911. Serial No. 631,052.

To all whom it may concern:

Be it known that we, WALTER S. ROCKEY and HILLIARY ELDREDGE, citizens of the United States, both residing at New York, 5 in the county of New York and State of New York, have invented certain new and useful Improvements in Furnaces, of which the following is a full, clear, and exact specification.

10 Our invention relates to furnaces of that type in which metal is fused on a hearth.

The object of our invention is to provide a furnace in which metal may be fused by exposing it to the direct action of the flame 15 and heat generated by a hydro-carbon or a carbonaceous fuel.

20 A further object of our invention is to provide a furnace in which the outlet for the burned gases and products of combustion and also imperfect combustion of the fuel used.

25 A further object of our invention is to provide a furnace in which the metal, after being fused, will be exposed to the action of the gases, vapors, products of combustion and products of gaseous and vapor decomposition produced or generated in the furnace, to serve as a covering to prevent oxygen 30 from coming in contact with the metal while it is in the furnace, and to purify the metal by the reducing action of the said products of combustion and gaseous and vapor decomposition.

35 A further object of our invention is to provide means for tilting the furnace to discharge the molten metal therefrom.

40 A further object is to provide a furnace having a tap-out constructed in such a manner that the gases generated in the furnace will protect same and prevent "freezing" 45 of the metal around the plug.

Further objects and advantages will be pointed out in the following specification.

45 Referring to the drawings which form a part of this specification, Figure 1 is a longitudinal sectional view through a furnace embodying certain features of our invention. Fig. 2 is a plan view of the furnace, 50 shown partly in dotted lines, and a cross sectional view through a portion of the chimney above the hood. Fig. 3 is a longitudinal sectional view through a furnace embodying our preferred form when de-

signed for use in fusing cathode copper 55 which is provided in sheet form. Fig. 4 is a sectional view on line 4-4 of Fig. 3, looking in the direction in which the arrow points.

Referring now particularly to Figs. 1 and 60 2, this furnace is especially adapted to the process of fusing and purifying copper, and in describing its operation we will assume that cathode copper is being fused in a hydrocarbon fuel flame and purified in the 65 furnace, it being understood, however, that any other metal may be fused in the same manner and also that a carbonaceous fuel could be used if desired.

A, indicates a foundation made of blocks 70 of stone or other suitable material, and B indicates our improved furnace, which is preferably made of molded silica, or built up of bricks of this material, or of other suitable material which is refractory to heat 75 and neutral to the metal to be fused and to the gases or other products generated directly or indirectly by the burning of the fuel used, as far as practicable.

C, indicates a circular fusing chamber, 80 the bottom of which serves as a hearth, and C' indicates an extension of said chamber which serves as a flue or delivery chamber for the heated gases and other products produced or generated in the furnace to flow 85 through and from the fusing chamber, and also serves as a conduit for the metal.

D, indicates an opening through which the metal may be introduced into chamber C, and D' indicates a cover for said opening should it be desirable to close same.

E, indicates a portion having the wall increased in thickness longitudinally relative to the thickness of the walls of the chamber C, for the purpose of forming the conduits 95 F-F', etc., of sufficient length to insure the proper admission and combustion of the gases therein in order to generate a reducing flame in the chamber C, and these conduits we prefer to make cone-shaped as 100 illustrated, and inclined downwardly and opening into the chamber C below the top of the inner wall of the chamber C' to cause the heated gases and other products to flow freely through said chamber to the 105 outlet G.

The portion E may be made semi-circular in form as illustrated and any desired num-

ber of conduits F may be formed therein, depending on the size of the chamber C, and the amount of metal it is desired to fuse per hour.

- 5 The bottom of the chamber C, and extension thereof C', is preferably inclined as illustrated, the lowest portion being located at the outlet, and a dam H is formed across the chamber C', adjacent the outlet G and 70
 10 a tap-hole H' is located near and extends through the base of the dam on a line with the bottom of the chamber C', and a plug I, is provided to fit the tap-hole as indicated. 75
 15 J, indicates a removable cap-piece which is provided with a ring-bolt J' by means of which the portion J can be lifted from the end of the furnace or replaced thereon. The portion J extends beyond the lower end of the body portion B to provide 80
 20 a deflecting surface J² by means of which the gases and other products produced or generated in the furnace may be deflected downward into the ladle K for the purpose of purifying the molten metal and protecting same from the atmosphere while it is 85
 25 flowing into said ladle.

L—L represent burners which inject and mix the hydro-carbon and air together in proper proportions to form a proper combustible, the air and hydro-carbon fuel being under pressure to cause the combustible mixture to flow through the conduits F—F and into the chamber C with considerable velocity. The dotted lines in the chamber 90
 30 C indicated by M—M, etc., indicate sheets of cathode copper which have been inserted in the furnace through the opening D, and N indicates the fused copper which is prevented from leaving the furnace by the 95
 35 dam H.

O, indicates a hood which leads to an outlet O' and which being provided with an exhaust fan serves to carry away the products of combustion to the exterior of the building in which the furnace may be located. 100
 40

In operating the furnace, the chamber C is first thoroughly heated by the burning of the fuel from the burners L—L and after the chamber C is thoroughly heated the 105
 45 cover D' is removed from above the opening D and the cathode copper plates are dropped through same into the chamber C where they rest on the bottom of the hearth, and as the metal is fused, it flows into the chamber C' against the dam H as indicated 110
 50 in the drawing, the gases and other products produced or generated by the combustion of the fuel in the meantime passing out through the opening G and being deflected 115
 55 downward into the ladle K. By removing or partially withdrawing the cone-shaped plug I, the metal flows through the opening H' into the ladle K while the highly heated products of combustion and gaseous 120
 60 and vapor decomposition are purifying and 125
 65

protecting the metal and also the tap-hole H' from contact with the outer atmosphere.

Referring now to the construction illustrated in Figs. 3 and 4, we will refer to the elements which correspond to the elements in Figs. 1 and 2 by small reference letters instead of capitals for the purpose of differentiating and yet readily comparing the constructions. a, indicates the foundation; b, the furnace; c, a rectangular shaped 75
 70 chamber and c' the extension thereof; d, the opening through which the metal is introduced into the chamber c; d' the cover for said opening; e, the thickened walls containing the fuel conduits f—f which in this 80 construction are rectangular in cross section and increase in area from the inlet opening to the full width of the chamber c where they open into said chamber, and are located at the top of the chamber instead of near the bottom as shown in Fig. 1. g, indicates the outlet from the furnace; h, the dam; h' the tap-hole; i, the plug; j, the cap-piece and j' the ring bolt therefor; j² the deflecting surface of the cap; k, the ladle; l—l the 90
 95 burners; m, the sheet of metal to be fused; n, the fused copper; o, the hood and o' the outlet therefrom. p, indicates a base piece which is supported on trunnions q mounted on the base a as indicated. r, indicates a lever operated gear wheel which engages with a rack p' formed on the curved surface of the base piece p, and by means of which the furnace is tilted to flow the fused metal over the dam instead of removing the plug 100
 100 i, and also serves to tilt the furnace in the opposite direction to cause the furnace extension c' to hold a greater quantity of fused metal, if required by circumstances. By this construction the heat is applied near the top 105
 105 of each sheet on each side thereof, and flows let downward in contact therewith to the bottom of the furnace so that the sheet fuses evenly. In other respects the operation and construction is the same as that hereinbefore set forth in the description of the construction set forth in Figs. 1 and 2.

We do not wish to be limited to the exact features of construction illustrated in the drawings submitted in this application, 110
 115 since the details of construction may be varied in some respects without departing from the broad invention disclosed, and, therefore, reserve all constructions which may come within the scope of the claims. 120

Having thus described our invention what we claim is:

1. A furnace comprising a chamber for the metal to be fused, an opening through which fuel may be introduced into said chamber to fuse the metal, an opening through which the metal may be introduced into said chamber, and an outlet from said chamber constructed to cause the fused metal and the gaseous products of combustion pro- 130

its inner periphery shaped to deflect the gases passing out of the delivery chamber in a downward direction while in such manner as to envelop the fused metal flowing from the chamber.

15. A furnace comprising a fusing chamber having its axis disposed vertically, an opening in the top of the chamber for feeding metal thereto, heating means arranged to project heating flames into the bottom of said fusing chamber, a delivery chamber connected to the fusing chamber and having its axis horizontally disposed, means at the end of the delivery chamber whereby the molten metal flowing from said delivery chamber will move in a downward direction and means at the end of the delivery chamber whereby the gases flowing through said delivery chamber will be deflected in a downward direction and in such manner as to surround the fused metal flowing from the delivery chamber.
16. A furnace comprising a vertical fusing chamber, a horizontal delivery chamber, a hood on the end of the delivery chamber having an opening below the bottom of the delivery chamber, a pivoted support for said chambers, together with means for moving said pivoted support and chambers.
- 30 17. A furnace comprising a vertical fusing

chamber open at the top, a cover therefor, a horizontal delivery chamber, a hood having an opening at the bottom thereof connected to the end of the delivery chamber, a pivoted support for the chambers, together with means for changing the position of the longitudinal axis of the delivery chamber from horizontal to that of an angle.

18. A furnace comprising a vertical fusing chamber, heating flues located at the rear of the fusing chamber, means for introducing gaseous fuel into the heating chambers, a delivery chamber situated in front of the fusing chamber and having its delivery end shaped to cause the metal to flow in a downward direction, and a hood at the delivery end of the delivery chamber shaped to cause the products of combustion flowing through said chamber to be turned downward to envelop the metal flowing out of the delivery chamber.

In testimony whereof, we affix our signatures, in presence of two witnesses.

WALTER S. ROCKEY.
HILLIARY ELDRIDGE.
